UNITED STATES PATENT OFFICE.

MOSES C. NIXON, OF CHICAGO, ILLINOIS.

APPARATUS FOR BALING PRESSES.

Application filed April 23, 1927. Serial No. 186,080.

My invention relates to improvements to apparatus adaptable to baling presses.

It is one of the objects of my invention to provide a press having a reciprocating plunger adapted to tamp or press the material in a suitable press box in which the driving means for the plunger is so arranged that the plunger is substantially at rest during a portion of each cycle of operation thereby affording opportunity to feed the material into the press box between the time the plunger is withdrawn from the press box and the time it re-enters the press box again thereby materially shortening the distance traveled by the plunger when out of the press box and thus making it feasible to make the apparatus much more compact and sturdier in construction than has been possible heretofore.

A further object of my invention is the provision of means whereby the mechanism for imparting movement to the plunger may be readily locked against operation whenever desired, as for instance when moving or shifting the press box and the like.

My invention contemplates the provision of a chute for feeding the material into the press box in combination with suitable feeding mechanism and it is another object of my invention to provide improved means whereby feeding of the material into the press box may be automatically cut off when the plunger descends into the press box and will remain cut off until after the plunger has been withdrawn therefrom.

More specifically my invention contemplates the provision of rotatable material feeding mechanism in the chute in combination with a gate which is adapted to swing into position to check the flow of material through the chute; and it is another object of my invention to provide means operating automatically for stopping the operation of the feeding mechanism and for swinging the gate into closed position as the plunger descends into the press box, said feeding mechanism remaining non-rotative and the gate remaining in closed position until the plunger has been withdrawn from the press box whereupon the feeding mechanism automatically

resumes operation and the gate is automatically withdrawn from the chute so that the material may flow from the chute into the press box.

The invention consists in the novel constructions, arrangements and devices to be hereinafter described and claimed for carrying out the above stated objects and such other objects as will appear from the following description of a certain preferred embodiment illustrated in the accompanying drawings of which,

Fig. 1 is a side elevational view of which an apparatus embodying the principles of my invention, the feed chute and mechanism associated therewith having been omitted.

Fig. 2 is a longitudinal sectional view of the apparatus taken on the line 2—2 of Fig. 1 showing the feed chute and its associated feeding mechanism attached to the apparatus.

Fig. 3 is a plan view.

Fig. 4 is a sectional view on an enlarged scale taken on the line 4—4 of Fig. 2.

Fig. 5 is a detail view of the clutch and associated parts through which power is transmitted to the feeder shaft.

Fig. 6 is a sectional view on an enlarged scale taken on the line 6—6 of Fig. 1.

Fig. 7 is a sectional view on an enlarged scale taken on the line 7—7 of Fig. 1.

Fig. 8 is a detail view on an enlarged scale showing the manner in which the pitman is connected to the drive chains; and

Fig. 9 is a sectional view taken on the line 9—9 of Fig. 8.

Like characters of reference indicate like parts in the different views.

The plunger operating mechanism of the press or tamper is mounted on a frame comprising a pair of relatively wide inturned channel members 10, which have their lower ends firmly secured, in any suitable manner, between a pair of transversely extending supporting channels 11, reinforced by angles 12 firmly secured to said frame members and the supporting channels 11 may be supported by any suitable means, not illustrated. The upper ends of

the channel members 10 are disposed between a pair of transversely extending castings 13, which are secured to the channel members 10 by bolts 14, the bolts extending through elongated slots 15, provided in said castings, thus making it possible to raise and lower the castings on the channel members 10.

The reciprocating frame that carries the plunger includes a pair of vertically extending members, which may be in the form of I-beams, which are secured together at their upper ends by a transverse bar 17 and are braced by the cross-bars 18. At their lower ends these I-beams extend between and are secured to a pair of transverse members 19, as by bolts 20, reinforced by firmly securing angle members 21 to the I-beams and the members 19. To the underside of members 19 are secured a plurality of slats 22, spaced apart for purposes that hereinafter will appear. The I-beams are slidably disposed within the channel frame members 10 and to this end suitable bearings 23 are bolted to the inner-sides of the frame channel members 10, the inner and side faces of said bearings engaging the web and flanges of the I-beams 16 and serves as guides on which the I-beams may freely slide.

The operating mechanism for the plunger includes a drive shaft 24, with a pair of pinions 25 firmly secured thereto and meshing with gears 26, respectively. As best shown in Fig. 2, a stub shaft 27 is disposed at each side, one end of each shaft being supported in a bearing carried by housing plates 28, said plates being secured to the frame members 10, as by bolts 29, while the other end of shafts 27 are disposed in bearings provided in a plate 30, which is secured to plates 28, as by bolts 31. A sprocket wheel 32 is loosely mounted on each of the stub shafts 27 and the outer hub of said sprocket wheels extend into the hub of the adjacent gear 26, which is firmly secured thereto, as by keys 33. A pair of endless chains 34 operates over the sprocket wheels 32 and travel in a triangular path and to this end they are trained over sprocket wheels 35 and 36. The sprocket wheels 35 and 36 are mounted on short stub shafts 37, one end of each shaft being supported in a bearing formed in the adjacent casting 13 and the other end of the shaft being supported in a bearing provided in a bracket 38 integrally formed with the adjacent casting 13. A pitman 39 is pivotally connected at its lower end to a fastening device formed of a pair of plates 40 with a filler 41 secured between and to the plunger members 19, as by bolts 41'. The pitman 39 at its upper end is pivotally connected between and to the endless chains 34, as by wrist-pin 34', with its respective ends secured to means 34'' carried by a pair of pivot pins extending inwardly from each of the endless chains (see Figs. 8 and 9), thereby forming an operative connection be-

tween the chains 34 and the pitman 39. The pitman may be of any suitable construction but preferably comprises a pair of channel members 42 disposed so that their flanges extend toward each other, with filler blocks, or full length members, disposed between the channel members. Fastening means such as rivets 44 extending through the channel members 42 and the filler blocks 43 securely fastening the channel members together against the opposite sides of the filler blocks, thereby forming a rigid structure.

It will now be apparent that upon rotating the drive shaft 24 the endless chains 34 will be caused to move over the sprockets 32, 35 and 36 in a triangular path, shown in Fig. 1, thereby, imparting a reciprocating movement to the plunger and causing the latter to descend into and be withdrawn from the press box 45. It will be noted that the plunger is substantially at rest while the upper end of the pitman 39 travels with the chains over the sprockets 35 and 36, there being substantially no movement imparted to the plunger while the upper end of the pitman is moving in a path substantially at right angles to the line of movement of the plunger. Since the plunger is at rest a portion of the time when out of the press box, it affords an opportunity to feed the material into the press box without the moving plunger interfering therewith. The mechanism for operating the plunger permits the apparatus as a whole to be positioned closer to the press box and the lower bearings 23 for the reciprocating I-beams 16 are maintained in closer relationship to the plunger when in its lowermost position of travel, than would be the case if the upper end of the pitman 39 were not carried around in a triangular path as described above. Adjusting screws 46 are threaded in the castings 13 and bear on the ends of the frame channels 10. It will be obvious that by loosening the nuts on the bolts 14 that the screws 46 may be turned down, which results in moving the castings 13 farther away from the sprocket 32 thereby tightening the chains 34.

The means for driving the shaft 24 comprises a driven pulley 47 loosely mounted on the shaft. A spider member 48 being firmly secured to the shaft, as by key 49, said spider member carrying radially slidably friction shoes 50. A hub member 51 slidably mounted on the shaft and the key 49, and links 52 connecting the hub member with the friction shoes, so that when the member 51 is moved toward the spider member the friction shoes engage a friction ring 53 carried by the pulley, the arrangement being such that when the parts are in the position shown in Fig. 4, the pulley is fixed to the shaft 24 and drives the latter. It is frequently desirable to lock the mechanism for reciprocating the plunger against movement, particularly when removing the bale box, to prevent the plunger

from descending by gravity to said box and interfering with the baling operations, and to this end I have provided a stationary member 54, which is carried by parts secured to the frame of the press. The clutch is normally operated by lever 55. It will be noted from Fig. 4 that the adjacent faces of the member 51 and the stationary member 54 are provided with teeth which are adapted to co-engage. The parts are so arranged that when the hub 51 is shifted toward the pulley 47 the pulley is locked to the shaft 24 and when the hub member 51 is shifted in the opposite direction the pulley is free to turn on the shaft and the hub member 51 non-rotatably engages the member 54 thereby locking the shaft 24 against rotation and preventing movement of the plunger and the operating parts.

20 The means for feeding the material to the press box includes a feed chute 56 supported by bars 57 and 58 attached to the frame work and material may be supplied to this chute in any suitable manner. Means for feeding the material from the chute into the press box includes a driven shaft 59 which carries a plurality of feed fingers 60. The shaft 59 carries a pulley 61 which may be driven by any suitable means, for instance a belt, not shown. I preferably also provide means for cutting off the flow of material through the chute at certain times during the operation of the apparatus and to this end I have provided a gate 63 adapted to be swung into and out of position with respect to the chute 56. The gate comprises a plurality of fingers secured to a rock-shaft 65 journalled in suitable bearings secured to the feed chute. The free ends of the fingers 64 are adapted to extend upwardly through suitable apertures provided in the bottom of the chute. Said apertures being protected by a plate 66, with a spacer between it and the bottom of the chute, the plate acts also as a guide for the fingers.

50 The shaft 59, with its feed fingers 60, may be operated continuously and the gate for cutting off the flow of material through the chute may be operated in any suitable manner but I prefer to operate the feeding and the cut-off mechanisms intermittently and to provide means for automatically starting and stopping the aforesaid mechanisms. In the embodiment illustrated the pulley 61 is loosely mounted on the shaft 59, and the clutch 67 is slidably mounted on and is rotatable with the shaft 59. When the clutch 67 is in operative position the pulley 61 is fixed to and drives the shaft 59. The clutch 67 normally is maintained in non-operative position so that power to the feeding mechanism is cut-off and the gate in the chute is normally maintained in closed position. The means for accomplishing these results preferably include an arm 68 fixed to the shaft 65,

the arm 68 carrying a weight 69 adapted to be adjustably positioned thereon. The weighted arm 68 tends to rotate the rock-shaft 65 counter-clockwise as viewed in Fig. 2, and thereby holds the gate in closed position in the chute. The shaft 65, also, carries an arm 70 which is connected by a rod 71 to an arm 72 fixed to the rock-shaft 73, which is carried by supports 74 and a brace 74'. The rock-shaft 73 carries another arm 75, which is connected by a rod 75' to clutch operating means 76 (see Fig. 5). The arm 75, rod 75' and means 76 are so arranged and constructed with respect to the clutch 67 that when the shaft 73 is rocked in a clock-wise direction, as viewed in Fig. 2, the clutch 67 is disengaged from the pulley 61 and the operation of the feeding mechanism ceases. The weighted arm 68, therefore, normally maintains the gate for the feed chute in a closed position and normally cuts off the power from the feeding mechanism in the chute. In order to apply power to the feeding mechanism and to open the gate automatically and at the proper time, I have provided a shoe or plate 77 on one of the reciprocating I-beams 16. A bell-crank 78 pivoted to a bracket carried by the frame of the apparatus, has one arm connected by a rod 79 to an arm 80 fixed to the rock-shaft 73 (see Fig. 3). One arm 90 of the bell-crank 78 may be provided with a roller for engagement with the end or curved portion of the plate 77.

100 In operation, as the plunger returns or moves upwardly the curve or upper end of the plate 77 engages the roller or arm of the bell-crank 78 and swings the latter counter-clockwise, as viewed in Fig. 2, which also turns the rock-shaft 73 in a counter-clockwise direction. Such movement of the rock-shaft 105 73 results in the clutch 67 being moved into engagement with the pulley 61, thereby connecting the power to the shaft 59 and the feeding mechanism, and it also results in the shaft 65 being rocked in a clockwise direction 110 thereby withdrawing the material cut-off mechanism from the chute. Then as the plunger descends toward the press box the bell-crank 78 is permitted to swing in a clock-wise direction and the weighted arm 68 causes 115 the shaft 65 to be rocked counter-clockwise, as viewed in Fig. 2, which moves the cut-off mechanism into position shown in dotted outline, cutting off the flow of material to the press box. The rock-shaft 65 when moved 120 in a clockwise direction, through rod 71, rocks shaft 73 counter-clockwise and disconnects the clutch from the pulley 61, thereby stopping the feeding mechanism. By the arrangement described, power is intermittently 125 and automatically applied to the feeding mechanism and the operation of the cut-off mechanism is automatically controlled.

I do not intend to limit my invention to the specific embodiment illustrated in the 130

drawings and described in the foregoing specification except only in so far as certain of the appended claims are specifically so limited as it will be obvious that changes 5 may be made without departing from the spirit of my invention.

I claim:

1. In apparatus of the class described the combination of a press box in which the bale 10 is formed, a reciprocating plunger operating in connection with said box, a feed chute for delivering material to said box, a gate pivoted to swing into and out of position in said chute, and operating means for said gate including a pivoted lever connected to said gate, and means operable upon the upward stroke of said plunger for swinging said lever into position to open said gate, thereby permitting delivery of material from the chute 20 to the bale box.

2. In apparatus of the class described, the combination of a bale box in which the bale is formed, a reciprocating plunger operating in connection with said box, a feed chute for 25 delivering material to said box, a weight-controlled gate pivoted to swing into closing position in said chute, and means for opening said gate including a pivoted lever connected to said gate and operable upon the upward stroke of the plunger for swinging said lever into position to open the gate, thereby permitting delivery of material from the chute to the bale box.

3. In apparatus of the class described, the 35 combination of a press box in which the bale is formed, a reciprocating plunger and operating means therefor, a feed chute for delivering material to said box and a gate pivoted to swing into and out of position in said chute, operating means for said gate including a pivoted bell-crank having one arm connected with said gate, and reciprocating means adapted upon the return stroke of the plunger to engage the other arm of the bell-crank thereby swinging the gate into open 45 position and permitting delivery of material from the chute to said box.

4. In apparatus of the class described, the combination of a press box in which the bale 50 is formed, a reciprocating plunger operating in connection with said box, a feed chute for delivering material to said box, a rock shaft extending transversely of said chute, a gate comprising a plurality of fingers fixed to said 55 shaft and adapted to swing into and out of position in said chute, and operating means for said gate including a pivoted lever connected with said rock-shaft, and means operable upon the return stroke of the plunger 60 for swinging said lever thereby imparting a rocking movement to said shaft to open said gate and permitting delivery of material from the chute to said box.

5. In apparatus of the class described, the 65 combination of a press box, a reciprocating

plunger operating in connection with said box, a feed chute for delivering material to said box, a rock-shaft extending transversely underneath the chute, a gate adapted to swing into and out of position in said chute 70 and comprising a plurality of fingers carried by said shaft and adapted to extend upwardly through the bottom of the chute, and operating means for said gate including a pivoted lever connected to said rock-shaft, 75 and means operable upon the return stroke of the plunger for swinging said lever to rock said shaft and withdraw the fingers from said chute and thus permitting delivery of material from the chute to said box.

6. In apparatus of the class described, the combination of a press box in which the bale is formed, a reciprocating plunger operating in connection with said box, a chute for delivering material to said box, feeding mechanism operating in said chute, material cut-off mechanism for said chute, weight-controlled means normally holding said cut-off mechanism in operative position and said feeding mechanism inoperative, and means operable upon the return stroke of the plunger for overcoming the effect of said weight controlled means thereby withdrawing the cut-off mechanism from the chute and causing said feeding mechanism to operate.

7. In apparatus of the class described, the combination of a press box, a reciprocating plunger operating in connection with said box, a chute for delivering material to said box, a rock-shaft beneath said chute, and a gate carried by said shaft and operable through the bottom of the chute whereby the flow of material may be cut-off from said box.

8. In apparatus of the class described, the combination of a press box, a reciprocating plunger operating in connection with said box, a chute for delivering material to said box, means for feeding material to said box, a rock-shaft beneath said chute, and a gate carried by said shaft and operable through the bottom of the chute whereby the flow of material may be cut-off from said box.

9. In apparatus of the class described, a reciprocating plunger, a pitman pivotally connected at one end to the plunger and power means embodying a triangularly disposed movable member connected to the other end thereof and so arranged as to cause that end of the pitman to travel in a substantially triangular path, the side of said triangular path farthest from the plunger being substantially transverse with respect to the line of movement of the plunger whereby the plunger comes to a rest at the end of its outward or non-working stroke, for the purpose 125 specified.

10. In apparatus of the class described, a reciprocating plunger, an endless flexible drive member, means for causing said flexible member to travel in a substantially triangu-

lar path with the side of said path farthest removed from the plunger in substantially a transverse position with respect to the line of movement of the plunger, a pitman pivotally connected at one end to said plunger and at its other end to said flexible member at a point such that its last named end travels through

said transverse portion of the flexible member when the plunger is at the end of its outward or non-working stroke thereby causing the plunger to be at rest at such time for the purpose specified.

MOSES C. NIXON.
